FORK CONSTRUCTION

Rene Samson, Westmount, Quebec, Canada

Application June 22, 1950, Serial No. 169,571

2 Claims. (Cl. 30—322)

1

Introduction

The present invention relates to the manufacture of kitchen and table articles, and more specifically to the manufacture of table forks designed for a special purpose, namely, the handling of alimentary paste foods such as spaghetti, vermicelli, or noodles.

Alimentary paste foods of this nature, when cooked, are rather difficult to handle in eating, especially when an ordinary table fork is used. When the food is in long lengths, as is common with spaghetti, the usual practice is to load the spaghetti on the fork by revolving the fork in one hand while pressing the spaghetti on the end of the fork with a spoon. If the spaghetti or noodles are in short lengths, this wrapping procedure becomes rather difficult, especially when there is only a small amount of food left on the plate and the fork has usually to be discarded, and the remainder finished with a spoon.

Applicant's development

The present invention recognizes this problem and aims to furnish a satisfactory solution by providing a novel table fork construction where-in the prongs are provided with teeth which are adapted to aid in the picking up and retaining of the food on the fork.

Accordingly, the present invention is a table fork adapted for use in the handling of alimentary paste foods and comprises, in combination, with the usual general fork structure having a plurality of spaced apart prongs, food retaining teeth on each of the prongs. The teeth are arranged so that the outer side surfaces of the outer prongs are smooth, with the inner side surfaces of the outer prongs and both side surfaces of the prongs between the outer prongs having at least one food retaining tooth.

A plurality of food retaining teeth are employed and are arranged in regularly spaced apart relationship extending from adjacent the open end of the prongs towards the handle portion. The teeth themselves are formed by a series of indentations or re-entrant notches extending inwardly from the side surfaces of the prongs, each indentation presenting a first face extending directly inwards substantially perpendicular to the longitudinal axis of the prong and a second face extending obliquely from the inner end of the first portion to the outer surface of the prong. This formation provides the inner surfaces of the prongs with a series of small saw-like teeth which are adapted to catch and retain spaghetti.

The present fork construction has substan-

2

tially the same space between the prongs as an ordinary fork, but the prongs themselves may be smaller so that the overall width of the fork may be less than that of an ordinary fork.

According to the construction of the invention the prongs are sufficiently spaced apart to allow entry of the prongs between the strands of a hank of spaghetti combwise with the prongs between the strands. The oblique faces of the notches and intervening unnotched surfaces are adapted to allow the inward sliding of the spaghetti without hindrance, while the perpendicular faces of the notches are adapted to hinder the spaghetti sliding outwards off the fork. The notches are sufficient in number and spaced apart effectively to engage a plurality of strands of spaghetti at once.

In the drawings:

Having thus generally described the nature of the invention, particular reference will be made to the accompanying drawings, and in which:

Figure 1 is a diagrammatic view in perspective elevation of a preferred fork construction embodying the invention.

Figure 2 is an enlarged view of the food engaging portion of the fork construction shown in Figure 1.

Figure 3 is an enlarged detail view of a portion of Figure 2 with the prongs shown in section along the line 3—3.

Figure 4 is a sectional view of Figure 2 along the line 4—4.

Figure 5 is a diagrammatic view in front elevation of the food engaging portion of a fork illustrating an alternative construction of the food retaining teeth.

Figure 6 is a sectional view of Figure 5 along the line 6—6.

Figure 7 is a sectional view of the prongs of a construction shown in Figure 5 as it would appear along the line 7—7.

Figure 8 is an enlarged detail view of a typical section of the inner prongs of the fork construction shown in Figure 5.

With particular reference to Figures 1 and 2 of the drawings, which illustrate a preferred construction of a table fork embodying the food retaining means according to the invention, 10 designates an elongated handle portion, and extending from the handle portion a substantially wider food engaging portion 12 having a plurality of spaced apart prongs 14. Each of the prongs 14 are of a substantially elliptical shape in general cross section and each include a series of spaced apart food engaging teeth 16. These teeth are disposed on the inner side sur-

face of each of the outer prongs and on both side surfaces of the prongs between the outer prongs. The food retaining teeth 16 are formed by a series of indentations along the marginal inside surfaces of the prongs, each indentation having a first portion that extends inwardly at right angles to the longitudinal axis of the prong, and a second portion which extends obliquely outwards from the inner end of the first portion to the outer surface of the prong. This arrangement forms a series of saw-like teeth along the inner surface of the prong which are adapted to catch and retain the alimentary paste food as it is picked up by the fork.

In the illustration shown, the teeth extend for approximately $\frac{2}{3}$ of the overall length of the prongs but it is also contemplated that they could extend for about $\frac{1}{4}$ or $\frac{1}{2}$ of the overall length of the prongs depending on the relative size of the fork and the particular use contemplated.

The edges of the teeth 16 are rounded to conform with the overall elliptical section of the prongs, and the outer surface of the outer prongs and the upper and lower surface of all the prongs are smooth and rounded so as to avoid any inconvenience when the fork is placed in the mouth.

In the alternative construction shown in Figure 5, the saw-like teeth are replaced by a series of outwardly extending projections 20 which extend along the inner side surfaces of the prongs 114 in a similar manner to the food retaining teeth 16 of the previously described construction. These projections or teeth 20 are disposed obliquely relative to the longitudinal axis of the prongs and are arranged in staggered relationship relative to each side of the inner prongs as shown in Figure 5. The general cross section of the prongs of this alternative construction is also of a substantially elliptical form and the outwardly extending teeth are blended into the prong body so as to leave a smooth upper and lower surface on each prong. In effect, the arrangement of the teeth of this construction is similar to the formation obtained by forming each prong in a spiral and then removing the outstanding projections on the upper and lower surfaces to reduce the prong to the desired elliptical cross section.

As in the previous construction, while the preferred construction illustrated shows the food retaining projections or teeth extending from adjacent the open end of the prongs upwardly along approximately $\frac{2}{3}$ of the overall length of the prongs, it is also contemplated that the teeth could extend only for about $\frac{1}{4}$ or $\frac{1}{2}$ of the overall length of the prongs, depending on the relative size of the fork and the contemplated use.

It has been found on experiment that table forks embodying food retaining means according to the invention when inserted and withdrawn from a mass of cooked alimentary paste food such as spaghetti, or noodles, the food passes between the prongs and is retained thereon so that it can easily be dished out or handled for eat-

ing. This presents a distinct advantage over the ordinary fork as the nature of foods of this type, when cooked, is such that it cannot be retained and simply falls off the fork unless it is wrapped around the prongs with the aid of a supplementary utensil.

I claim:

1. A table fork useful for eating cooked spaghetti and having substantially the general structure of a conventional table fork including an elongated handle and a shank from which extend at least three substantially equally spaced apart blunt-ended prongs all of substantially the same length having outer ends remote from the handle, being two outer prongs and at least one inner prong, the outer prongs having outer side surfaces which are smooth and blunt inner side surfaces provided with a plurality of re-entrant notches, said inner prong having both side surfaces provided with a plurality of spaced apart re-entrant notches, each notch being shaped so as to provide a tooth having a face substantially perpendicular to the axis of the fork, having a base at the inner part of the notch and a face oblique to the axis of the fork extending from said base to the side surface of the prong in a direction towards the handle, each tooth having a blunt outer face parallel to the side surface of its prong, each prong being substantially symmetrical in cross section whereby its thickness is about the same at its inner and outer sides, the prongs being so spaced apart as to allow the entry of the prongs into a hank of spaghetti combwise with the strands of spaghetti between the prongs, the oblique faces of said teeth being adapted to allow the inward sliding of the spaghetti between the prongs without hindrance, said substantially perpendicular faces being adapted to catch the strands of spaghetti and to hinder their sliding outward off said prongs, and the notches being spaced apart effectively to engage a plurality of strands of spaghetti at once and thus to hinder their sliding from the fork, said notches extending from adjacent the free ends of the prongs a major portion of the length thereof.
2. A table fork, according to claim 1, which has two inner prongs, both said inner prongs having both side surfaces provided with a plurality of spaced apart re-entrant notches.

RENE SAMSON.
